UNITED STATES PATENT OFFICE.

ISAAC L. RHEUTAN, OF RICHMOND, VIRGINIA.

ENVELOP-FASTENER.

SPECIFICATION forming part of Letters Patent No. 761,911, dated June 7, 1904.

Application filed July 30, 1903. Serial No. 167,553. (No model.)

To all whom it may concern:

Be it known that I, ISAAC L. RHEUTAN, of the city of Richmond, county of Henrico, and State of Virginia, have invented certain new and useful Improvements in Envelop-Fasteners; and I do hereby declare that the following is a full, clear, and exact description thereof, reference being had to the accompanying drawings, forming a part of this specification, 10 and in which—

Figure 1 represents what is commonly known as a "merchandise-envelop" with my improved fastener applied thereto, the top flap being shown open preparatory to placing the 15 printed matter or merchandise therein and sealing the same. Fig. 2 is a similar view to Fig. 1, with said top flap folded over and fastened. Fig. 3 represents, upon an enlarged scale, a transverse section taken on line *a*, Fig. 20 1 looking in the direction of arrow *a'*, all the following figures being on the same enlarged scale. Fig. 4 represents my improved fastener in blank form preparatory to bending and applying it to the envelop, and Fig. 5 is 25 a bottom view of the same with the holding-clips bent over onto the body of the fastener.

My invention relates to metal fasteners, and more especially to those made from sheet metal, for use on what are commonly termed 30 "merchandise-envelops" whose top flap is not gummed, but provided with an eyeleted opening to receive the prongs of the fastener in fastening said top flap to the body of the envelop.

Said invention consists of a fastener whose body in blank form is provided with a fastening-clip at both ends of the body portion, with two oppositely-projecting prongs extending 35 at right angles from opposite sides of said body and clips formed on the body in alignment with said prongs, as and for the purpose hereinafter more fully set forth.

To enable others to better understand the nature and purpose of my said invention, I 40 will now proceed to describe it more in detail.

In the drawings, A represents an ordinary manila merchandise-envelop made in the usual way and having the usual ungummed open flap A' at the top, which is provided with the eyeleted opening B.

C represents my improved metal fastener, whose prongs C' C' are passed through said eyeleted opening B in fastening the flap A', as hereinafter described. Said fastener C consists of the central part or body C², the aforesaid prongs C' C', the side clips C³ C³, and the end clips C⁴ C⁴. The prongs C' C' project at right angles from opposite sides of the body C² in this instance, the inner edges thereof being shown in alinement. These long prongs C' C' have their inner edges C⁵ substantially in alinement. By "inner" edges it will be seen from Fig. 4 of the drawings that the longitudinal edges of such prongs nearer the center portion of the body C² are intended. The 55 clips C⁴ C⁴ are formed by bending the ends of body A, as is shown by the last four figures of the drawings, and the clips C³ C³ by extending a portion of the metal out from each side of body A upon the opposite side of and 60 in alinement with the prongs C' C'. By this construction of employing four fastening-clips, one on each side of body A, said body and its prongs may be held securely upon all 65 four sides, and thus prevents the fastener 70 from becoming loose or readily torn from the envelop after having been fastened thereto. It will be observed that by arranging the long prongs, as shown, with their inner edges in alinement it admits of the clips C³ C³ being 75 arranged in alinement with said prongs on opposite sides of said body, thereby reinforcing the prongs and holding the device securely in position in the operation of bending 80 said prongs to fasten the loose flap of the envelop.

In securing the fastener to the envelop the clips C³ C³ C⁴ C⁴ are passed through the body near the open end thereof and then bent 85 against the inner surface of said envelop to hold them thereto, as is shown in Figs. 3 and 5, the body of the fastener being located at the proper place to admit of its prongs being passed through the eyeleted opening in flap A', when the latter is folded down against 90 said body; as is shown in Fig. 2. The fastener is designed to come centrally between the two sides of the envelop and near the open end thereof, as previously stated and shown 95 in Figs. 1 and 2. In fastening the flap A' 100

down the prongs C' C' are passed through the eyeleted opening B, said flap folded against the body of the envelop, and said prongs then bent down against the outer surface of the flap in a similar manner to other fasteners of this class. The construction of the fastener is such, as will be obviously seen, as to bring one of the side clips C³ and part of the two end clips C⁴ C⁴ through the usual central double overlapping edge D of the envelop, and thereby greatly facilitates holding the fastener securely from being torn from said envelop. The fastener when thus secured, as aforesaid, is firmly held against any lateral strain by the end clips C⁴ C⁴ and against the strain imparted by bending the prongs in fastening down the flap A' by the side clips C³ C³. This feature of holding the fastener against the pressure of bending the prongs, in conjunction with that of holding said fastener against lateral strain, is the essential feature and advantage which I claim for my invention over the common well-known envelop-fasteners of this class. I do not, however, claim broadly the use of a metal fas-

tener for the purpose described, as there are several fasteners of different constructions patented and in use employed for the same purpose. I therefore limit my invention to the specific construction set forth and pointed out in the claim. 30

Having described said invention, what I claim as new, and desire to secure by Letters Patent, is—

An envelop-fastener, consisting of the main body whose ends form holding-clips adapted to be passed through the envelop and bent against the inner surface thereof, long prongs projecting laterally from opposite sides of said body, whose inner edges are substantially in alinement, and holding-clips projecting laterally from opposite sides of the body, one side clip being in alinement with one prong, and the other with the other prong, substantially as and for the purpose set forth. 35 40 45
